ACCOUNTING MACHINE

Edward J. Carey and Lawrence D. Kilheffer, Dayton, Ohio, assignors to The National Cash Register Company, Dayton, Ohio, a corporation of Maryland

Application February 12, 1948, Serial No. 7,758

44 Claims. (Cl. 235—61.6)

1

This invention relates to accounting and similar business machines, and more particularly to the type of accounting machines used by banking and similar institutions, wherever, as a part of a business system, it is necessary or desirable to pick up data, such as an Old Balance, whether it be a debit balance or a credit balance, from records previously prepared, as an incident to the type of system used in the institution.

The invention is adapted to be used in machines of the general type disclosed in the following United States Letters Patent:

Bernis M. Shipley, No. 1,619,796, dated March 1, 1927; Bernis M. Shipley, No. 1,789,418, dated January 20, 1931; Bernis M. Shipley, Pascal Spurlino and Everett H. Placke, No. 2,262,258, dated November 11, 1941; Mayl A. Goodbar, No. 2,305,000, dated December 15, 1942; Everett H. Placke, No. 2,351,541, dated June 13, 1944; and Pascal Spurlino, Everett H. Placke, Willis E. Eickman and Arthur G. Kramer, No. 2,373,510, dated April 10, 1945.

Such records of the type mentioned in the first paragraph may be in the form of cards, sheets or tapes, etc., having thereon magnetic areas, or perforations, or printed or written characters designating the data to be picked up to be recorded in the machine embodying the present invention; and from such magnetic areas, perforations, or printed or written characters, definite data may be picked up, under control of the same, and recorded in said machine.

More specifically this invention relates to an automatically operated and electrically controlled keyboard, controlled by record cards, sheets or tapes, etc., of the type above mentioned, wherein said prepared records control the selection of the various amount determining devices or keys, which selected devices or keys, after selection and upon automatic operation thereof, control differentially adjustable devices to enter into the totalizers of the machine, and to set appropriate printing mechanisms in the machine, with the amounts corresponding to the values of the automatically selected and automatically operated manipulative devices or keys.

Moreover, the above mentioned keyboard is unique in its construction in that, in addition to its being electrically controlled and automatically operated, it can also be manually operated without in any way interfering with a previous or a subsequent automatic selection and operation of the devices or keys. Thus, variable amounts or data may be set up on the keyboard manually by the operator, or such variable

2

amounts or variable data may be automatically picked up from record cards, sheets or tapes, and the devices or keys corresponding to the amounts or data picked up are automatically selected, and such automatically selected keys are also automatically operated whereby such amounts or data are entered into the machine through a differentially adjustable mechanism under the control of said devices or keys to transmit said data to appropriate totalizers and appropriate printing mechanism.

Such differential mechanisms, totalizers, and printing mechanisms, are disclosed in several of the above mentioned patents.

Only that much of said types of machines is shown herein as is necessary to properly illustrate the present invention, and for a more detailed description and illustration of such machines reference may be had to the patents above mentioned.

There are machines known wherein electrically operated devices have been superimposed above amount keys on adding machines, which devices are electrically operated for the purpose of depressing keys under control of perforated cards, to set up amounts corresponding to those represented by the perforations on the cards.

However, applicants' invention is entirely different from that in this respect, in applicants' invention, while the keys are automatically selected by electrical devices and are automatically depressed, such automatic mechanisms do not in any way interfere with the manual selection and depression of any of the same groups of keys. In the illustrated form the invention is applied to what are known in the art as "flexible" amount key banks, where, when manually operated the depression of any key in a bank releases any other previously depressed key in the same bank.

Thus, the machine to which applicants' invention is applied may be operated automatically under the control of record cards, sheets or tapes, etc., having thereon magnetic areas or perforations, or printed or written characters, designating the data to be recorded in the machine. This same machine may be also operated by manual selection of keys and manual depression thereof to control the machine to record and accumulate data according to the manually selected and manually operated keys.

Therefore, it is an object of the present invention to provide a novel keyboard for a machine of the type above mentioned, which novel keyboard may be operated either automatically or manually.

It is another object of the present invention to provide a keyboard for machines of the type above mentioned, wherein the keys may be electrically selected and those electrically selected keys automatically depressed to control the machine to accumulate and record data according to the selected and operated keys.

It is a further object of the present invention to provide a keyboard for types of machines above mentioned, wherein the keys thereof may be automatically selected and automatically depressed, or said keys may be manually selected and manually depressed for the purpose of controlling the machine to accumulate and record data according to the keys which have been either automatically or manually selected and depressed.

It is a further object of the present invention to provide a keyboard for machines of the above type, the keys of which are each provided with a movable device which is adapted to be automatically moved from a non-controlling into a controlling position under control of electrical devices.

It is a further object of the present invention to provide a keyboard of the type above mentioned wherein each key has a movable key pin connected to the armature of a solenoid such pin adapted to be moved from a non-effective into an effective position upon the energization of its associated solenoid.

A further object of the present invention is to provide machines of the type above mentioned with mechanism for performing a preliminary or auxiliary cycle prior to the regular machine cycle for the purpose of automatically selecting any of the keys and then automatically depressing the electrically selected keys whereby those keys, after having been automatically depressed by means operable during the auxiliary cycle, control differential mechanism in the machine to accumulate and record data, according to the selected and operated keys.

It is a further object of the present invention to provide a machine of the above mentioned type and having the novel keyboard associated therewith, with means for performing a preliminary or auxiliary cycle prior to the regular cycle of the machine, and to provide means to prevent the regular machine releasing mechanism from becoming effective until substantially the end of the auxiliary cycle.

It is a further object of the present invention to provide a machine of the above type with a single motor having a plurality of clutch or driving devices operable by said motor, for the purpose of driving a portion of the machine through an initiatory or preliminary cycle, such preliminary cycle mechanism being driven by one of the clutches from the common motor, and at the same time preventing the other clutch from being operated during the auxiliary cycle, and providing for the release of the second clutching mechanism to drive the machine through its regular cycle following the auxiliary cycle, which control mechanism renders the second clutch release mechanism effective near the end of the auxiliary cycle.

It is still a further object of the present invention to provide machines of the above mentioned type with a novel keyboard mechanism, the keys of which are adapted to be automatically selected under the control of cards, sheets or tapes, having thereon magnetic areas, or perforations, or printed or written characters, des-

ignating the data to be accumulated and recorded in the machine.

With these and incidental objects in view the invention includes certain novel features of construction and combinations of parts illustrated in a preferred form or embodiment of which is hereinafter described with reference to the drawings which accompany and form a part of this specification.

10 In the drawings:

Fig. 1 is a side elevation of an amount key bank, the keys of which may be automatically selected and automatically depressed to control the differential positioning of the amount differential means here shown; or said keys may be manually selected and depressed to control said amount differential means.

Fig. 2 is an enlarged view, partially in section, showing one of the keys, its automatic selecting means, and a part of its operating or depressing means.

Fig. 3 is a wiring diagram of the control circuits rendered effective to release the auxiliary clutch to initiate the starting of the preliminary or auxiliary cycle.

Fig. 4 is a plan view, partly in section, showing the automatic selecting means for one of the keys, and a part of its operating means.

Fig. 5 is a diagrammatic view showing the keys in section, and the wiring diagram for automatic selection of the keys.

Fig. 6 is a side elevation showing the preliminary or auxiliary cycle mechanism for the machine and a part of the controls for the machine release.

Fig. 7 shows the balance pickup and overdraft keys, the auxiliary cycle releasing switch, and a portion of the means to release the machine.

Fig. 8 is a front elevation showing part of the machine releasing mechanism for the auxiliary cycle and for the main cycle of operation.

Fig. 9 is a detail of a part of the machine releasing mechanism, showing the coupling between two sections of the machine release shaft.

Fig. 10 shows the main cycle release clutch and associated means, and the drive from the motor clutch to the main cam shaft of the machine.

Fig. 11 shows the main switch for closing the circuit for the auxiliary cycle and the main cycle of operation.

General description

Described in general terms, the invention invention includes novel keyboard mechanism for machines of the type mentioned at the outset of this specification, and particularly those machines which are adapted to be used in banking institutions, other types of financial institutions, and as a matter of fact, wherever records are made where, as a part of the system of keeping those records it is necessary and essential that old balances be set in the machine to which new accounts are either added or subtracted, and finally the new balance is arrived at and a record made thereof.

More specifically the keys of each of the key banks of the keyboard, and particularly the amount key banks, are arranged to be electrically selected through means of a selective circuit closing device which functions to pick up the old balance from magnetic spots or perforations, or printed or written characters designating the

data to be picked up to be recorded, after which the selected keys are automatically depressed.

These selecting and depressing operations of the keys of the novel key banks all take place in what has been termed herein a preliminary or auxiliary cycle of the machine, which cycle is initiated prior to the regular operation of the machine during which regular operation the differential mechanisms, the printing mechanisms and totalizers are controlled according to the positions and values of the keys which have been automatically selected and depressed.

To accomplish the above purpose, and in the preferred form of the invention, the machine is provided with an electric motor and two clutching mechanisms which clutching mechanisms are adapted to be released in a predetermined timed relation so that one of them drives the machine through its preliminary cycle and the other drives the machine through its regular cycle.

It might be well to state here that during the preliminary cycle the main cam shaft and the differential mechanisms of the machine do not function, but are held in an idle position all during the preliminary cycle.

There are provided two separate clutch release mechanisms for the machine, but when the machine is released only the clutch release mechanism associated with the preliminary cycle is fully released to allow its associated clutch to drive the preliminary cycle mechanism. At this time the regular clutch release mechanism is held in an inoperated position by mechanism which is operated during the releasing of the auxiliary clutch mechanism, and is held in such idle position until substantially near the end of the preliminary cycle, at which time the main clutch releasing mechanism is rendered effective, whereupon the main cycle of operation automatically takes place immediately following the auxiliary cycle, without any other depression of keys or levers by the operator.

In other words, a depression of the balance pickup key or the overdraft pickup key closes a switching mechanism which completes a circuit to energize a solenoid, which trips the machine release shaft and releases the auxiliary clutch, and the motor starts.

At this time the card carriage, or table, such as that shown in the Shipley, Spurlino and Placke Patent No. 2,262,258, and also the Spurlino, Placke, Eickman and Kramer Patent No. 2,373,510, is moved into position. Upon this card carriage or table, there has been previously placed a card or other type of control medium having thereon either magnetic areas or perforations, or printed or written characters, designating the balance which is to be picked up, and the selective circuit controlling or closing device which is diagrammatically shown herein, functions to pick up the old balance from the magnetic spots or perforations or from the characters on the control medium, which has been placed on the carriage. During this preliminary or auxiliary cycle the auxiliary cam line operates a portion of the machine release shaft which is associated with the amount keys only, to release any amount keys that might have been depressed accidentally. The auxiliary cam line operates a shaft line to pull in or depress the keys which have been selected under control of said magnetic spots or perforations or characters on the control medium.

The auxiliary section of the machine release shaft, the auxiliary clutch and the auxiliary motor switch are then restored, after which the

regular clutch release lever trips the regular clutch for the regular cycle of the machine, whereupon the old balance which has been picked up from the magnetic spots or perforations or characters on the control medium, through the differential mechanism, is set up in the printing devices and accumulated in the balance totalizer, which balance totalizer, as is well known in the art, is what is known as a crossfooter, that is, an add and subtract totalizer.

Operating mechanism

As above mentioned, the machine is particularly adapted to be driven by an electric motor, which is not shown in full in this application, but there is shown a worm 20 (Fig. 8), driven by the motor, which worm 20 drives a worm gear 21 secured to a clutch driving shell 22, which will be known herein as the main driving clutch. This worm gear 21 is also secured to a clutch driving shell 23, which will be known herein as the auxiliary clutch.

Both of these clutch driving shells 22 and 23 are substantially like that shown in the above mentioned Shipley Patent No. 1,619,796, and also in the United States Patent No. 2,060,249, granted to Howard B. Scott on November 10, 1936.

Cooperating with the inner surface of the shell 22 is a clutch ring 24, which also cooperates with a roller 25 "floating" between two studs (not shown) carried by a clutch roll disc 26. This roller 25 cooperates with the inner surface of the shell 22 and the periphery of the ring 24. The ring 24 surrounds an eccentrically mounted driven member 27 fastened to a gear 28 and mounted on the sleeve 29 (Fig. 10) of said gear. The clutch roll disc 26 is mounted on the hub of a stop cam 30 rigidly secured to the member 27 and the gear 28. Mounted on the hub of the gear 28 is a switch cam 31 having secured thereto a stop block 32. Surrounding the hub of the switch cam 31 is a torsion spring 33 having one end wrapped around the lower end of the block 32 and the other end wrapped around a stud 34 carried by the stop cam 30.

A shoulder 35 of the clutch roll disc 26, a shoulder 36 of the stop cam 33, and the upper edge of the block 32 normally engage the lower end of a clutch release lever 38 mounted on a stud 39 on the machine frame 40. This lever 38 maintains the clutch members 26, 28, 31 and 32 in their normal inactive positions.

An arm 41 of the clutch release lever 38 (Figs. 8 and 10) carries a roller 42 which normally rests upon the curved edge 43 of a lever 44 fast on a shaft 45, which extends across all of the amount key banks in the machine and has bearings in the frame 40 and an arm (not shown). When the lever 44 is rocked counter-clockwise (Fig. 10) to release the machine, in a manner to be herein-after described, the lever 38 is rocked counter-clockwise and is thereby disengaged from the shoulders 35 and 36 and also from the block 32, by a spring 47. Counter-clockwise movement of the lever 38 is limited by a stud 48, carried on the frame 40. Upon operation of the lever 38 in the manner fully illustrated and described in the above mentioned Shipley Patent 1,619,796, the worm 20 drives the gear 21 and shell 22, and the spring 33 rocks the clutch roll 26 to force the roller 25 into a position to wedge the ring 24 against the inner surface of the shell 22 and presses the ring tightly against one side of the driven member 27, so that the shell 22, the roller 25, and the ring 24 operate as a single unit to

drive the member 27 and the gear 28, which is secured thereto, as is fully illustrated and described in the above mentioned Scott Patent No. 2,060,249.

The movement of the switch cam 34 by the spring 33 rocks lever 50 (Figs. 10 and 11) whereupon the upper end of said lever engages a roller 51, carried by a lever 52 pivoted to the motor frame, and moves the free or right end of said lever downwardly as viewed in Fig. 11, to cause an insulated portion 53 of said lever to move a pair of contact springs 54 into engagement with contact points 55, thereby closing the circuit through the motor to drive the worm 20 as above mentioned.

The gear 28 and its sleeve 29 are journaled on a stud 62 carried by the frame 40. This gear 28 meshes with an intermediate gear 64, which in turn meshes with a gear 65 secured to a main shaft 66 of the machine. Through this gearing the cam shaft 66 is rotated once during each main operation or cycle of the machine.

For the purpose of restoring the lever 38 to locking position near the end of the operation of the machine, a link 67 is pivoted at 68 to the arm 41 of the lever 38. The gear 64 carries a stud 69, which near the end of the operation of the machine engages a curved surface 70 of the link 67 and raises the latter, thereby moving the arm 41 and consequently the lever 38 clockwise to their normal positions, and into the path of the shoulders 35, 36, and block 32, to stop and hold the clutch members 26, 30 and 31 in their normal positions.

As will be hereinafter described, the lever 44 is rocked clockwise to normal position just before the stud 69 passes out of engagement with the bottom surfaces 70 of the link 67 in order to retain the lever 38 in its normal position.

The operation of the clutch release lever 38 has been above described as taking place during a normal adding operation of the machine.

However, in connection with the present invention, wherein, as above stated, there is a preliminary or auxiliary cycle of the machine prior to the main cycle of the machine, this lever 38 is positively controlled by means operable during the preliminary or auxiliary cycle to prevent the release of this lever at any time during the preliminary or auxiliary cycle. This clutch release lever 38, however, is also controlled so that it will be released automatically at the end of the preliminary cycle, whereupon the machine will automatically be permitted to go through its main or regular cycle of operation, whereby the differential mechanism will be set up under control of the amount keys which have been automatically selected and automatically depressed during said preliminary or auxiliary cycle. Mechanism for so controlling this main clutch release lever 38 will be described in connection with the description of the auxiliary cycle mechanism.

Preliminary or auxiliary cycle

As above stated, the machine is adapted to perform a preliminary cycle, which involves certain novel mechanism associated with the regular mechanism, to control the clutch release lever 38 so that it will not be released until the end of the preliminary cycle.

As previously pointed out, this preliminary cycle is for the purpose of automatically selecting the amount keys and then automatically depressing those selected keys.

There are other functions of the preliminary

cycle and mechanism to perform those functions, which will be set out in detail in connection with the description of this auxiliary cycle.

When the machine is operated and used to compute records from a previous balance, which balance may be in the form of magnetic spots, perforations, or printed or other characters on a record medium, from which, through electrical means, the amount keys are automatically selected, such type of operation is initiated by the depression of either a balance pick-up key 71 (Fig. 7) or an overdraft pickup key 72. These keys are mounted in the usual key frame 73, which is supported on rods 74 and 75, in turn supported by the machine frames 40 and 46.

The key 71 and the key 72 each has a pin 76 and 77 respectively, which cooperates with an angular surface 78 and 79 respectively of a slide 80 mounted on pins 81 carried by the key frame 73. This slide 80 has a projecting finger 82 adapted to cooperate with a switch blade 83 to close the contacts of the switch 84 whenever the slide 80 is moved to the right by the depression of either the balance pickup key 71 or the overdraft pickup key 72. As can be seen from Fig. 7, whenever either of the keys 71 or 72 is depressed, its pin 76 or 77, through the angular surface 78 or 79 will move the slide 80 to the right, whereupon the finger 82 contacts the switch blade 83 and moves the same to the right to close the contacts of the switch 84.

The circuits closed by this switch will be hereinafter described at the proper time.

The auxiliary clutch, including the shell 23 (Fig. 8) is comprised of a clutch ring 85, a roller 86, a clutch roll disc 87, a driven member 88, a stop cam 89, a switch cam 90, a stop block 91, and a torsion spring 92, connected to a stud 93 on the stop cam 89 and to the lower edge of the stop block 91. A shoulder 94 of the clutch roll disc 87, a shoulder 95 of the stop cam 89, and the upper edge of the stop block 91, normally engage the lower end of an auxiliary clutch release lever 98 to maintain the clutch members 87, 89, 90 and 91, in their normal positions. The above described clutch members are substantially identical with the main clutch members which have been previously described, and when released function in substantially the same way as the clutch members of the main clutch.

The auxiliary clutch lever 98 (Figs. 6 and 8) is pivoted on a stud 99 carried by an auxiliary side frame 100. An arm 101, integral with the clutch release lever 98, carries a stud 102 cooperating with the surface 103 of a clutch release control lever 104, secured to an auxiliary release shaft 105. This shaft 105 is in axial alignment with the release shaft 45, as shown in Fig. 8, and is supported by the auxiliary frame 100 and the hub 106, rigid with the main release lever 44.

When the release shaft 105 is rocked counter-clockwise, as will be hereinafter described, the lever 104 is rocked in the same direction, and the surface 103 passes from beneath the stud 102, whereupon a spring 107 connected to the auxiliary clutch release lever 98 rocks this lever 98 counter-clockwise until it is stopped by a limit stud 108 carried by the auxiliary frame 100. Upon this counter-clockwise movement of the clutch release lever 98 the worm 20 drives the worm gear 21 and shell 23, and the auxiliary clutch members are set in position by the spring 92 to cause the shell 23, the roller 86 and ring 85 to operate as a single unit to operate the driven member 88 to drive a gear 109 in exactly

the same manner as the regular driven member 27 drives the gear 28 in connection with the regular clutch.

The movement of the switch cam 99 rocks a lever 110 (Fig. 11) like the lever 50, which lever 110, through its engagement with a stud 111 on a lever 112, rocks said lever to cause an insulated bar 113, carried thereby, to move the switch contact springs 54 into engagement with the contact points 55, thus closing the main motor switch to drive the worm 20 in exactly the same manner as was described in connection with the movement of the lever 50 when the clutch release lever 38 is released.

The gear 109 meshes with an intermediate gear 124, which in turn drives the gear 125 secured to an auxiliary drive shaft 126 supported by the auxiliary side frame 108 and a sub-frame 123. Near the end of the preliminary cycle, the auxiliary clutch lever 98 is restored to its normal position by means of a link 127 pivoted at 128 to the arm 101 of the clutch release lever 98. The stud 129, carried by the gear 124 engages a surface 130 of the link 127 and raises the link, and consequently rocks the lever 98 clockwise to its normal position just before the end of the preliminary or auxiliary cycle.

The machine release shaft in the present case is divided into three sections namely, shaft 45 which extends from the left side frame 46 of the machine to a point near the right side frame 46, as shown in Fig. 8, an auxiliary shaft 105, which has been previously described, and a third shaft 141 (Figs. 8 and 9). The shaft 45 extends across all of the amount banks in the machine, and the shaft 141 of the machine release shaft extends only across the control banks of the machine, which control banks are, as is well known in the art, located to the right of the amount bank. There are usually three control banks in the machine, a portion of one of which is shown in Fig. 7.

There is a coupling between the shaft 141 and the shaft 45, and another coupling between the shaft 45 and shaft 105, which couplings will be hereinafter described, and which are for the purpose of permitting the shafts 45 and 105 to be released upon the depression of the Balance Pickup key 71 or the Overdraft Pickup key 72, which are shown in Fig. 7.

The Balance Pickup key 71 and the Overdraft Pickup key 72 cooperate directly with the release shaft 141, and when either of these keys is depressed this shaft 141 is permitted to move in a clockwise direction as viewed in Fig. 7, or counter-clockwise as viewed in Fig. 9.

The release mechanism and couplings for the release shaft will now be described. Cooperating with the keys 71 and 72 (Fig. 7) is a control bar 142 adapted to be moved toward the left by the depression of either one of these two keys.

This control bar 142 is mounted at its lower end by means not shown, which is pivoted on the lower stud 81, and at its upper end on an arm 143, pivoted on the upper stud 81. The arm 143 carries a pin 144 cooperating with an arm 145 of a yoke 146 pivoted on a rod 147 supported by the machine frame. Integral with the yoke 146 and arm 145 is an arm 148 normally held in front of an arm 149 secured to the machine release shaft 141. A spring 150 connected to a stud in the arm 145 holds the latter in its normal position. A spring 151 is tensioned between a stud on the arm 145 and the usual non-repeat pawl 152.

From the above description of the parts it can

be seen that when either the Balance Pickup key 71 or the Overdraft Pickup key 72 is depressed the movement of the bar 142 to the left rocks the arm 143 clockwise, whereupon the pin 144, through the arm 145 and yoke 146, rocks the arm 148 counter-clockwise against the tension of the spring 150 until the arm 148 is moved above the arm 149. When this occurs, the shaft 141 is immediately moved in a clockwise direction, as viewed in Fig. 7, and counter-clockwise as viewed in Fig. 9 by the following mechanism. Secured to the shaft 141 is an arm 156 carrying a stud 157, which supports a pair of members 158 (only one of which is shown), and the lower ends of which are surrounded by a coil compression spring 159 compressed between shoulders on the members 158 and the end of a slot 160 in a link 161 which also surrounds the stud 157. This last described mechanism is old and well known in the art, and fully illustrated and described in the above mentioned Shipley Patent 1,619,796.

From the above description it will be clear that when the arm 148 is moved upwardly, thus releasing the arm 149, the spring 159, being under compression, will exert its power through the members 158 to rock the arm 156, and consequently the shaft 141, in a counter-clockwise direction as viewed in Fig. 9. This is clockwise as viewed in Fig. 7.

When this movement of the shaft 141 occurs, an arm 162 (Figs. 8 and 9), secured thereto, is moved in a counter-clockwise direction, whereupon a pin 163 carried by an arm 164, secured to the shaft 45, is released to permit the arm 164 and shaft 45 to move in a counter-clockwise direction as viewed in Fig. 10, under the influence of a spring 165 secured to the previously described lever 44.

Therefore, upon release of the shaft 141, through the coupling members 162, 103, and 104, the shaft 45 is permitted to move in a counter-clockwise direction, as viewed in Fig. 10, under the influence of the spring 165.

It will be recalled from the previous description that the depression of either the Balance Pickup key 71 or the Overdraft Pickup key 72 closes the switch 84 (Fig. 7). The closing of this switch closes a circuit to be later described, to energize a magnet 171 (Fig. 6) having secured to its core member an arm 172, to which is pivoted at 173 a link 174, carrying a pin 175, which projects into a slot 176 of an arm 177 secured to the shaft 105, as shown in Figs. 6 and 10. When the pin 175 is moved to the left under the influence of the energized magnet or solenoid 171, said pin 175 is moved into the path of a surface 178 of an arm 179, which is secured to the hub 106 of the lever 44, which it will be remembered is secured to the release shaft 45. The link 174 is forked at its upper end and is normally held

against the shaft 105 by a spring 160. From the above description it will be clear that when the lever 44 is rocked counter-clockwise, as viewed in Fig. 10 by its spring 165, and after the pin 175 has been moved into the path of the surface 178 of the arm 179, this arm 179 by its engagement with the pin 175 will move the arm 177 in a counter-clockwise direction. Thus, the shaft 105 and the lever 104 secured thereto are rocked counter-clockwise.

It will also be recalled that when the arm 204 is moved in a counter-clockwise direction, as just mentioned, its surface 103 moves from beneath the stud 102 of the auxiliary clutch release lever 98, thus releasing the auxiliary clutch

mechanism so that it can be driven by the clutch shell 23, shown in Fig. 8, to drive the auxiliary mechanism shown in Fig. 6 through one cycle prior to the regular cycle of operation of the machine.

It is necessary, at this time, to prevent the release of the main clutch release lever 38 (Fig. 10) when the clutch release lever 98 is released. This is accomplished by the following means:

The arm 177, which has just been described, is provided with a finger 182, which cooperates with a stud 183 carried by the arm 41 of the main clutch release lever 38. As the arm 177 is moved counter-clockwise (Figs. 6 and 10) the finger 182 is moved directly beneath the stud 183 prior to the time that the surface 43 of the lever 44 is moved from beneath the stud 42 of the arm 41; therefore, even though the lever 44 and the shaft 45 are moved into their released positions by the spring 165, the main clutch mechanism cannot be released because at this time the main clutch release lever 38 is held in its normal position by the finger 182 having been moved directly beneath the stud 183 on said lever 38.

From the description of the above mechanism it will be clear that upon the depression of either the Balance Pickup key 71 or the Overdraft Pickup key 72, the three sections of the release shaft, namely, 141, 45 and 105 (Figs. 6, 8 and 10) are released and caused to move under the influence of their springs 159 and 165 through the coupling members 162, 164 and 179, and pin 175, to effect a release of the preliminary or auxiliary mechanism so that this mechanism may be driven through one cycle of operation just prior to the main cycle of operation. It will also be clear that while the shaft 45 is released the main clutch shell 22 cannot drive the main clutch mechanism and the gear 28 because the main clutch release lever 38 is locked in its normal position by the finger 182 and stud 183 during such auxiliary cycle.

Near the end of the preliminary cycle the shaft 105 is restored to its normal position, and when this occurs the finger 182 is moved from beneath the stud 183, whereupon the spring 47 rocks the main clutch release lever 38 counter-clockwise, as viewed in Fig. 10 to release the main portion of the clutch so that the clutch shell 22 can drive the gear 28 in the manner previously described, to drive the main cam shaft 66 of the machine.

The means for restoring the shaft 105 to its normal position will now be described. The intermediate gear 124 (Fig. 6) meshes with a gear 184 which is mounted on a short shaft 185, supported by the frames 100 and 123. Secured to the side of this gear 184 is a disc 186, having a cam race 187, which cooperates with a flat sided stud 188 carried by an arm 189 which is secured to the shaft 105. The cam slot 187 has a wide section 190 so that when the shaft 105 is released and rocked counter-clockwise in the manner previously described, the flat stud 188 will be moved to the right into this wide section 190 of the slot 187. As the gear 184 and the disc 186 are given one complete rotation in a counter-clockwise direction during the auxiliary or preliminary cycle, near the end of this cycle the cam race 187, through its engagement with the pin 188, rocks the arm 189 clockwise back to the position shown in Fig. 6, whereupon the shaft 105 and the mechanism thereon is moved likewise.

During this clockwise restoring movement of

the shaft 105 the arm 177 is moved likewise, and during the first part of this restoring movement the finger 182 is released from beneath the stud 183 so that the spring 47 (Fig. 10) can rock the main clutch release lever 38 counter-clockwise to release the main clutch so that it will be driven by the main clutch shell 22 to drive the gear 28 to operate the main cam shaft 66 of the machine.

Before the arm 104 is restored clockwise to its normal position, the stud 129 (Fig. 6) will have moved the clutch release lever 98 clockwise to its normal position through the engagement of the stud with the bottom of the link 127 so that as the lever 104 reaches its normal position it will pass beneath the auxiliary clutch release lever stud 102, thus locking the auxiliary clutch mechanism in its home position.

Should any of the amount keys have been depressed prior to the beginning of the auxiliary cycle of the machine, there is provided a device operated during the auxiliary or preliminary cycle for automatically releasing any amount keys in the machine which might have been accidentally depressed. This mechanism is as follows:

Secured to the shaft 185 is a plate cam 191 (Fig. 6) which cooperates with a roller 192 on a lever 193 pivoted on a stud 194 carried by the frame 100. The upper portion of this lever 193 has an offset arm 195 (Figs. 6 and 8). The stud 192 is normally held against the plate cam 191 by a spring 196. This offset arm 195 cooperates with a long stud 197 (Figs. 8 and 10) carried by the release lever 44. As the gear 184 is rotated counter-clockwise, and near the middle of the cycle of operation, the cam plate 191 rocks the lever 193 counter-clockwise, whereupon the offset arm 195, by its engagement with the stud 197, rocks the lever 44 in a clockwise direction to automatically release any amount keys which may have been accidentally depressed prior to the beginning of the auxiliary cycle. The means which actually releases restores the keys will be hereinafter described.

To insure that the gear 184 and all of the parts connected therewith are brought to their normal positions at the end of the preliminary cycle, the plate or disc 186 is notched as at 198 to cooperate with a stud 199 on an arm 200, which is pivoted on the stud 194. The stud 199 is held always in contact with the periphery of the disc 186 by a strong spring 201 so that should momentum cause the gear 184 and disc 186 to be moved slightly past normal position in a counter-clockwise direction at the end of the preliminary cycle, the spring 201, through the pin 199 will restore the disc 186 in a clockwise direction to its normal position and this will also insure that the gear 124 and all the gears meshing therewith are in their normal positions at the end of this preliminary cycle.

The intermediate gear 124 meshes with a gear 202 (Figs. 6 and 8) which is mounted on a short shaft 203, supported by the frames 123 and 100. Secured to the gear 202 is a plate cam 204, which cooperates with, and controls a normally closed electric switch 205, the purpose of which will be hereinafter described.

The previously described gear 125 (Fig. 6) has cut in the side thereof a cam race 206, into which projects a roller 207 carried by a lever 208 pivoted on a stud 209 supported by the frame 100. Pivoted to this lever 208 is a link 209 which in turn is pivoted to an arm 210 secured to a

shaft 211 supported by the frame 100, and brackets 212, which in turn are carried by a bar 213 supported by the frames 40 and 48, as viewed in Fig. 8.

The configuration of the cam race 206 is such that during the preliminary or auxiliary cycle the shaft 211 is rocked first counter-clockwise and then clockwise to normal position, as viewed in Fig. 6. As viewed in Fig. 1, this direction is first clockwise and then counter-clockwise. This shaft 211 also has secured thereto an arm 214 connected by a link 215 to a key operating slide 216, the purpose of which will be hereinafter described in connection with the key bank mechanism.

Regular cycle operation

When it is desired to perform a regular cycle of operation for the purpose of adding an amount into the totalizers or for subtracting an amount from the crossfooter the operator manually selects the amount keys 271 representing the amount desired and manually depresses or operates such keys. He then depresses, for example, a motorized or machine release key 219 (Fig. 7) having a pin 220 which cooperates with the control bar 142. This pin 220 upon depression of the key 219 moves the bar 142 to the left to rock the arm 148 counter-clockwise away from the front of the arm 146 secured to the shaft 141 thus releasing this shaft 141 to the action of the spring 159 which rocks the shaft 141, and coupling arm 162 to permit the spring 165 (Fig. 10) to rock the shaft 45 and release control lever 44 counter-clockwise to release the clutch release lever 38, whereupon the regular clutch shell 22 is permitted to operate the gear 28 to drive the machine through a regular cycle of operation.

Since the key 219 does not cooperate with the slide 80 (Fig. 7) the switch 84 is not closed and consequently the magnet 171 is not operated and therefore the auxiliary release shaft 105 is not released thus preventing the operation of an auxiliary cycle when the amount keys 271 are manually selected and manually operated followed by a depression or operation of the machine release key 219.

Machine release controlling circuits

As previously described, this invention involves the automatic selection and operation of amount keys which automatic selection and operation are performed in what has been termed herein, a preliminary or auxiliary cycle of the machine which occurs immediately preceding the regular or main cycle of the machine. It has also been described how the main cycle of operation takes place automatically immediately following the preliminary or auxiliary cycle.

To initiate the auxiliary cycle requires the depression of either the balance pickup key 71 or the overdraft pickup key 72 which are shown in Fig. 7. The depression of either of these keys, as previously described, closes the switch 84 to energize the magnet 171 (Fig. 6) to move the coupling pin 175 into coupling position so that the auxiliary shaft 105 may be released through the action of the machine release shaft 45 and the machine release shaft 141 in the manner previously described.

The circuits to control the energization of the magnet 171 are illustrated in Fig. 3 in a dia-grammatic form and will now be described.

In connection with these circuits, there is secured to the gear 202, which is operated only during the preliminary cycle, a cam 221 which cooperates with a switch 222 to normally hold that switch closed.

The closing of the switch 84 by either the balance pickup key 71 or the overdraft pickup key 72 establishes a circuit from a positive potential of 100 v. D. C., through line 223, through the switch 84, line 224, switch blade 225, line 226, line 227, to a relay 228. From the relay 228 through line 229 to ground 230 thus completing the circuit to energize and operate the relay 228.

The circuit just completed energizes the relay 228 which attracts the three switch blades 231, 232 and 233 to close the following circuits.

The magnet 171 is in a separate circuit of 115 volts, A. C. 60 cycles and when the switch blade 232 is operated by the energization of the relay 228 a circuit is completed from line 234 of the 115 volt circuit through the switch blade 232, through line 235 to the magnet 171 and thence to line 236 to the opposite side of the 115 volt circuit thus energizing the magnet 171 to couple the auxiliary release shaft 105 to the release shaft 45 to effect the release of the auxiliary clutch release lever 98 in the manner previously described.

The energization of the relay 228 through the movement of the switch blade 233 closes a circuit from the positive line 223, through line 240, switch blade 233, line 241, relay 242, line 243 to the ground 230 thus energizing relay 242. The energization of relay 242 operates the switch blade 225 and a switch blade 244. The operation of the relay 242 closes a holding circuit for itself from line 223, switch 84, line 224, switch blade 244, line 245 to point 246, through the relay 242, and line 243 to ground 230. The operation of this relay 242 also by its operation of the switch blade 225, opens the key operated circuit by breaking the contact between the switch blade 225 and line 226.

The relay 228 is now held in operated condition by a circuit from the line 223 through line 251, switch blade 231, line 252, to switch 222 which is still held closed by the cam 221, and from switch 222, through line 227, relay 228, line 229 to the ground 230.

At an approximate 195 degrees time in the auxiliary cycle, the cam 221 releases the switch 222 permitting it to open and thus breaking the circuit through the relay 228 whereupon the switch blades 231, 232 and 233 are released, thus breaking the circuit at the switch blade 232 for the magnet 171 and breaking the main circuit to the relay 242 at switch blade 233. However, the relay 242 is still held by its holding circuit

from the positive potential through line 223, switch 84, line 224, switch blade 244, line 245, to point 246 through the relay 242, line 243 to the ground 230.

Due to the fact that the switch 222 is closed just before the end of the preliminary cycle it is necessary to hold this relay 242 active at this time in order to keep the circuit for the relay 228 open at this time at the point between the switch blade 225 and line 226 because the switch 84 remains closed at the end of the preliminary cycle and also during the regular cycle which follows the preliminary cycle, until the depressed balance pickup key 71 or the depressed overdraft pickup key 72 is restored near the end of the regular cycle.

Amount keys

As has been previously stated, the amount keys in the present invention are adapted to be automatically selected and the automatically selected keys automatically depressed, the automatic selection being under the control of magnetic spots or perforations, or other controlling characters on a control medium such as a card or tape, or any other type of medium which is desired and convenient to use in the machine. It has also been previously stated that these same keys may be operated manually, that is, they may be manually selected and manually depressed.

In the present application there is shown only one bank of amount keys, but it is to be clearly understood that as many banks, like that shown, may be used as is necessary, depending upon the capacity of the keyboard which is desired in the particular business in which the machine is being used.

The selected and operated or depressed keys control differential mechanism of the usual type shown and described in the above mentioned patents, which differential mechanism in turn controls the accumulation upon the totalizers and also controls printing mechanism such as shown in the above mentioned patents.

In Figure 1 there is shown one bank of amount keys and its associated differential mechanism. This bank of keys is what is known as a "flexible" key bank as previously stated. In each of the amount banks of keys there are nine amount keys 271 (Figs. 1 and 2) which are supported in the usual type of key frame 272 mounted on the rods 74 and 75. Each key 271 carries a pin 273, which projects from both sides of the key stem, to cooperate with a controlling bar 274 and a locking detent 275. The controlling bar 274 is pivoted at its upper end to an arm 276 pivoted on a stud 277 supported by the key frame 272. The lower end of the controlling bar 274 is pivoted on an arm 278 supported on a stud 279 carried by the key frame 272. This arm 278 cooperates with a pin 280 in an arm 281 secured to a short shaft 282, to which is also secured the usual zero stop pawl 283. A spring 284 normally holds the pin 280 against the arm 278. Depression of any one of the amount keys moves the controlling bar 274 downwardly, whereupon the arm 278 by its contact with the pin 280 rocks the zero stop pawl 283 counter-clockwise from its effective position shown in Fig. 1 to an ineffective position, so that the differential mechanism to be hereinafter described can be set under the control of the depressed key.

Also when one of the keys is depressed, its stud 273 moves the locking detent 275 downwardly until the pin is beneath a hook 285 on the detent, whereupon a spring 286 rocks the detent back to its normal position to retain the key in its depressed position. When a key 271 is manually depressed, the movement of the detent by the pin 273 releases any key 271 that might have been depressed in the same key bank. This type of key bank is known in the art as a "flexible" key bank. This locking detent is supported at its upper end by an arm 287 pivoted on the stud 277, and at its lower end on an arm 288 pivoted on the stud 279. The usual springs 289, one associated with each of the key pins 273, normally retain the keys 271 in their outer or undepressed positions.

Each of these keys 271 is normally longer than those shown in the above mentioned patents,

and each of said keys 271 has secured thereto a coupling pin carrier 301 (Figs. 1, 2 and 4), in which is slidably mounted a lightweight coupling pin 302 having an annular groove 303 engaged by a lip 304 of an armature 305 of an electromagnet 306 mounted in a bracket 307 secured to the top of the key frame 272.

The armature 305 is freely pivoted in a slot 308 in the side 309 of the electromagnetic bracket 307. A compression spring 310 is extended between a stud 311 on the armature 305 and a finger 312 on the bracket 307. This spring 310 normally holds the armature 305 in the position shown in Fig. 4, whereupon the hollow pin 302 is held in a position wherein its inner end is inside the side face of the key 271.

The previously described key operating slide 216 (Figs. 1, 2 and 4) lies adjacent the sides of the keys 271 and is mounted to slide on studs 313 and 314 carried by brackets 315 and 316, respectively, which brackets are secured to the top of the key frame 272. The slide 216 has slots 317 and 318 which surround the pins 313 and 314. This slide 216 is provided adjacent each of the pins 302 with a camming notch 319, the purpose of which will be hereinafter described.

As shown in Fig. 1, there is an electromagnet 306 and associated mechanism cooperating with each one of the keys 271. These electromagnets are adapted to be controlled by magnetic spots or perforations, or other printed or written control characters on a control medium 320, which may be a card or slip or tape. This control medium 320 is shown diagrammatically in Fig. 5 in connection with the wiring diagram for this invention.

When any one of the electromagnets 306 is energized by means to be hereinafter described, it attracts its armature 305, which is rocked counter-clockwise as viewed in Fig. 4, whereupon the lip 304 moves the pin 302 inwardly with relation to the carrier 301 and projects the inner end of the pin 302 beyond the key 271 and into its associated camming notch 319 of the operating slide 216.

This energization of the magnet 306 occurs during the first part of the preliminary cycle which has been above described, after which the shaft 211 (Fig. 1) is rocked in a clockwise direction by means of the cam race 206 (Fig. 6) in the manner which has been previously described. This movement of the shaft 211 through the arm 214 and link 215, moves the key operating slide 216 to the right, as viewed in Fig. 1, whereupon one of camming notches 319 engages the projected end of the associated pin 302, which has been moved inwardly by the energized magnet 306 thus depressing its associated amount key 271 to move its lower end into the path of a differential mechanism to be hereinafter described, to control the extent of movement of that differential mechanism.

When a key 271 is so depressed by the automatically operated key operating slide 216, its associated pin 273 operates the locking detent 275 in the manner previously described, whereupon the automatically depressed amount key 271 is retained in its depressed position at the end of the preliminary cycle and during the regular cycle of the machine which follows, in order that the differential mechanism shown in Fig. 1 and to be hereinafter briefly described, will be controlled by the value of the key which has

been automatically selected and automatically depressed.

Near the end of the preliminary cycle the electromagnet 306 is deenergized by having the circuit thereto broken, whereupon the spring 318 restores the armature 305 to its normal position and through the lip 304 simultaneously draws the pin 302 out of cooperation with the camming notch 319 of the key-operating slide 216. After this occurs the cam race 286 (Fig. 6) rocks the shaft 211 counter-clockwise (Fig. 1) to its normal position, which restores the key operating slide 216 to its normal position shown in Fig. 1. The slide 216 is held in sliding position on its studs 313 and 314 by a cover plate 321, which is secured to the top of the key frame 272 and also secured to the ends of the studs 313 and 314.

Circuit for key selecting magnets

The circuit for controlling the energization of the magnets 306 will now be described. Secured to the bracket 316 (Fig. 1) is a ten-wire plug 322, nine of the wires which run between insulating sheets 323 and 324 (Fig. 2). One of these wires goes to each one of the electromagnets 306 and the tenth wire is fastened to the frame as a ground wire. The ten wires from the ten-wire plug 322 are adapted to be put into a ten-wire socket 325 shown diagrammatically in Fig. 5, the wires from which lead to a selective circuit closing device 326, also shown diagrammatically in this Fig. 5.

Let it be assumed that there is a magnetic spot or a perforation or a printed or written control character in the "8" position of the control medium 320, shown diagrammatically in Fig. 5. In this case the electromagnet 306 associated with the "8" key 271 will be energized and the circuit for the energization of this magnet is as follows:

From the ground 331, through battery 332, switch 295, line 333, line 334, into the selective circuit-closing device 326, through the perforation or control character on the control medium 320, indicated at the point of the arrow 335, to line 336. From the line 336 the circuit continues to the socket 325, to the plug 322, through line 337 to the electromagnet 306 associated with the "8" key 271, from this electromagnet 306 to line 338 to line 339, through the plug 322, socket 325, to ground 340. The magnets 306 are all normally partially energized by means of a holding circuit, later described, and thus the above circuit causes the selected magnets to be fully energized. Therefore the magnet 306 associated with the "8" key, attracts its armature 305 to move its associated pin 302 into the camming notch 319 of the key-operating bar 216.

When the magnetic spots on the control medium 320 are used to control the selecting magnets 306, such spots cause electrical impulses in the circuit by means of appropriate amplifiers to perform a function similar to that performed by perforations, that is, to close the circuit. Said impulses are sufficient to cause full energization of the selected magnets whereupon such fully energized magnets attract their respective armatures to actuate or move their associated pins 302 into their related camming notches 319 of the key-operating bar 216.

Since it is contemplated controlling the above described circuit by a scanning movement of the control medium 320, there is a normally closed holding circuit for the magnet 306, which is as follows:

From the ground 331, battery 332, switch 205, line 333 to line 341, resistor 342, line 343, to the line 336, and thence through the socket 325, plug 322, line 337, magnet 306, line 338, line 339, and back to the ground 340.

This holding circuit, through the resistor 342, is maintained until near the end of the preliminary cycle of operation and is opened when the low portion 344 of the cam 244 comes adjacent the switch 245, thus permitting this switch to open and break the holding circuit for the magnet 306.

This low position 344 covers sufficient time in the cycle of its operation to permit the thus de-energized magnet 306 to release the armature 305 whereupon the spring 318 restores the pin 302 in the manner above described. However, the key 211 at this time is in its depressed position, but the armature 305 and lip 304 are long enough, as viewed in Fig. 2, so that the lip 304 still engages the pin 302 while the key 211 is in its depressed position.

From the above description it will be clear that whenever there is a magnetic spot or a perforation or a printed or written control character on the control medium 320 opposite any one of the wires 333 in the selective circuit controlling device that the electromagnet 306 will move the pin 302 and thus automatically select an amount key, depending upon the relative value position of the magnetic spot or perforation, or printed or written control character on the control medium 320. Such automatic selection of the keys 211 occurs during the preliminary cycle, and during this same preliminary cycle of the machine said automatically selected key is automatically depressed by operation of the key-operating slide 216 in the manner previously described. Thus, the differential mechanism which will be herein-after briefly described is controlled as to its extent of movement by the automatically selected and automatically operated key.

Differential mechanism

The differential mechanism shown in this case is that shown in connection with one single amount bank, and is substantially identical with the amount differential mechanisms shown in many of the above mentioned patents, and therefore only a brief description thereof will be given herein.

Depression of any one of the amount keys 271, either automatically or manually, rocks the zero stop pawl 233 associated with that particular denomination counterclockwise out of the path of a reset spider 351, free on a hub of an amount differential actuator 352 rotatably supported on a bushing 353 extending between two hangers or support plates 354 (only one here shown) said plates being in turn supported by rods 355 and 356 extending between the main frames 43 and 46. There is a pair of supporting plates 354 for each amount differential and a tie rod 357 extends through the holes in the center of the bushings 353 to secure all of the amount differentials in a compact unit.

A notch in the forward end of the spider 351 engages a stud 358 in a forward extension of a bell crank 359 pivoted on an extension of the actuator 352. Carried by the vertical arm of the bell crank 359 is a stud 360 on which is pivoted an arm 361. The arm 361 is also pivoted to the upper end of a latch 362 pivotally mounted on the actuator 352. The latch 362 has a foot 363 normally held in contact with the periphery of a driving segment 364 just above a shoulder 365 thereon.

by means of a spring 366. The driving segment 364 is rotatably supported on the hub of the actuator 352. A link 367 pivotally connects the driving segment 364 to a cam lever 368 pivoted on a stud 369 in the left-hand one of the plates 354, said lever 368 carrying rollers 370 and 371 which coact with the peripheries of cams 372 and 373, respectively, secured on the main cam shaft 66. Depression of any one of the amount keys 271 moves the lower end thereof into the path of a rounded surface 374 of the bell crank 359.

In adding operations, or in other words, in the main cycle of operation which immediately follows the previously described preliminary or auxiliary cycle, the main shaft 66 and cams 372 and 373 make one clockwise revolution, causing the lever 368 to rock the driving segment 364 first clockwise and then counter-clockwise back to normal position. Clockwise movement of the segment 364 causes the shoulder 365 thereon, in co-operation with the foot 363 of the latch 362 to carry the latter and the amount actuator 352 clockwise in unison until the rounded surface 374 contacts the stem of the depressed key 271. This rocks the bell crank 359, and through the arm 361, the latch 362 counter-clockwise to disengage the foot 363 of the latch from the shoulder 365 to arrest the clockwise movement of the actuator 352 and to position said actuator according to the value of the depressed amount key 271. Disengagement of the latch 362 moves the rounded extension of the arm 361 into engagement with the corresponding one of a series of locating notches 375 in a plate 376 secured between the rod 356 and an upward extension of the left-hand supporting plate 354.

After the latch 362 is disengaged from the shoulder 365, an arcuate surface 377 on the segment 364 moves opposite the foot 363 to retain the latch in its set position.

When the lever 368 reaches the terminus of its clockwise movement a roller 378 carried thereby coacts with an arcuate surface 379 on a beam 380 pivoted on a stud 381 carried by the actuator 352, and forces a concaved surface on the upper edge of said beam 380 into contact with the hub of the actuator 352 to move the rearward end of the beam into a position commensurate with the value of the depressed amount key.

The rearward end of the beam 380 is bifurcated to engage a stud 391 in a link 392, the lower end of which is pivotally connected to a segmental arm 393 which is used to set up type wheels of a column printing mechanism of the type fully illustrated and described in a patent to Charles H. Arnold No. 2,141,332 and embodies an application of the well known principle of driving mechanism disclosed in the United States patent to Walter J. Kreider No. 1,693,279.

From the above described mechanism it is clear how the differential actuator 352 is set under control of the depressed one of the amount keys 271.

Each of the actuators carries three sets of gear teeth 394, 395 and 396 which cooperate with lines of totalizers 397, 398 and 399, respectively, to cause the value of the amount key depressed to be accumulated into the selected one or ones of the totalizers on the lines 397, 398 and 399, in a manner which is well known in the art and which is also fully illustrated and described in several of the above mentioned patents.

Key release

Near the end of the main cycle of operation, any of the depressed amount keys 271 which have been

depressed either automatically or by hand are released by mechanism which is fully illustrated and described in the above Shipley Patent No. 1,789,418, which mechanism rotates the shaft 45 in a counter-clockwise direction, as viewed in Fig. 1, whereupon a member 400 secured to the shaft 45 contacts the arm 287 upon which the locking detent 275 is mounted, and moves the locking detent downwardly or toward the front to release the hook 285 from above the pin 273 of the depressed key, whereupon the associated key spring 289 will restore the key to normal undepressed position. After this movement of the shaft 45 it is moved slightly clockwise back to its normal position, whereupon the spring 286 restores the locking detent 275 to its normal position shown in Fig. 1.

As previously stated any amount keys 271 that might have been depressed, manually, prior to an auxiliary cycle of operation, are automatically released during such auxiliary cycle of operation so as not to interfere in any way with the automatic selection and automatic depression of such amount keys during the preliminary cycle of operation. It will be recalled that the arm 195 (Figs. 6 and 8) of the lever 193 by its engagement with the stud 197 rocks the lever 44 (Fig. 10) in a clockwise direction. This lever 44, being secured to the shaft 45, rocks said shaft 45 clockwise (Fig. 10), which is counter-clockwise as viewed in Fig. 1. Therefore, the member 400 is rocked counter-clockwise during such preliminary cycle of operation and said member 400 by its engagement with the arm 287 moves the locking detent 275 to release any hook 285 from any pin 273 of any key 271 that might have been depressed prior to the preliminary cycle of operation. Any such released key 271 will then be restored to its normal undepressed position by its spring 289.

Operation

It is felt that the detailed description of the mechanisms and the operations of the various sections of the machine of the present invention have been quite fully described, and therefore it is thought that only a brief description or resume of the operation will be necessary at this point.

A depression of the Balance Pickup key 71 or the Overdraft Pickup key 72 closes the switch 84, which completes the circuit to energize the electromagnet 171, which effects the tripping of the auxiliary release shaft 105, which is permitted, as described in detail through the couplings between the shaft 105 and the shaft 45, and between the shaft 45 and the shaft 141, under the control of the regular releasing mechanism shown in Fig. 9, initiated by the spring 159. This movement of the auxiliary shaft 105 releases the auxiliary clutch release lever 98 and the motor starts. The control medium 320 having thereon either magnetic spots or printed or written control characters, or having therein perforations is placed in the selective circuit controlling device 326 (Fig. 5) to control the pick up of the old balance or the overdraft from these magnetic spots or perforations, or other control printed or written characters on the control medium 320. During this part of the operation the proper electromagnets 306 are energized to control the setting of the pins 302 into cooperative relation with their key-operating slides 216, to select the proper amount keys 271 after which these slides 216 are operated to depress any of the selected amount keys 271.

to control the differential mechanism to be set according to the old balance picked up.

The auxiliary release shaft 105 is then restored and the auxiliary clutch release lever 98 is restored, whereupon the main cycle clutch release lever 38 is released and the gear 28, through the main clutch mechanism drives the main cam shaft 66 through its regular one cycle of operation. During this operation the differential mechanism shown in Fig. 1 is set under the control of the values of the depressed amount keys, whereupon such amounts are, through this differential mechanism, set up on printing mechanism through the medium of the segment 393 by means fully illustrated and described in the above mentioned Arnold and Krieder patents, and at the same time these same amounts are accumulated in the selected one or ones of the totalizers 397, 398, or 399.

As has been previously pointed out, these same amount keys 271 may be manually operated without in any way affecting the automatic selection thereof as has been described previously. When it is desired to use the machine manually and depress the keys manually, the key release shafts 141 and 45 are released but the electromagnet 171 is not energized, and therefore the stud 175 (Fig. 5) remains in the position shown, and consequently the coupling, consisting of the stud 175 and arm 179, does not operate, and therefore the auxiliary shaft 105 is not released. In order that the arm 179 can rock counter-clockwise, as viewed in Figs. 6 and 10, upon the release of the release shaft 45, there is a clearance notch 401 in the arm 179 which moves over the stud 175 without in any way affecting any movement of the stud 175 when the machine is manually operated, that is, when the amount keys 271 are operated by hand instead of automatically through the selection of the various electromagnets 306.

Therefore, it can be seen that the present invention provides a novel keyboard mechanism wherein the keys thereof may be operated either manually by manual selection and manual depression, or they may be automatically selected and automatically depressed, the automatic operation in no way affecting the manual operation, and vice versa, the manual operation in no way affecting the automatic selection and operation of these keys. This of course greatly enhances the value of this type of keyboard mechanism because of the much wider range of usage to which it may be put.

While the form of mechanism herein shown and described is admirably adapted to fulfill the objects primarily stated, it is to be understood that it is not intended to confine the invention to the one form or embodiment herein disclosed, for it is susceptible of embodiment in various forms.

What is claimed is:

1. A bank of depressible keys adapted to be manually selected and operated and also adapted to be automatically selected by remote control; means carried by each of said keys and adapted to be moved relatively thereto to effect selection thereof; means operated by remote control to selectively move the first mentioned means; and means cooperating with the selected one of the first mentioned means to automatically operate its associated key.

2. A bank of depressible keys adapted to be manually selected and operated and also adapted to be electrically selected and automatically operated; means carried by each of said keys and

adapted to be moved relatively thereto to effect selection of said key; selectively operated means to selectively actuate said first mentioned means; and automatically operated means to cooperate with said selectively actuated means to operate its associated key.

3. In a machine of the class described, the combination of a bank of depressible keys adapted to be manually selected and manually operated; a slideable member carried by each of said keys; and selectively operable electrically-actuated means cooperating with said members to selectively actuate said members to select the associated key for operation.

15 4. In a machine of the class described, the combination of a bank of depressible keys adapted to be manually selected and manually operated; a slideable member carried by each of said keys; selectively operable electrically-actuated means cooperating with said members to selectively actuate said members to select the associated key for operation; and a member automatically operable and common to all of said slideable members to cooperate with the selected 20 and actuated slideable member to operate its associated key.

25 5. In a machine of the class described, the combination of a group of depressible keys, said keys adapted to be manually selected and manually depressed; a member carried by each key and adapted to be moved relatively thereto in a direction at right angles to the direction of movement of said key while being depressed; and selectively operable automatic means cooperating 30 with each of said members to selectively move any one of the members relatively to its associated key to automatically select said associated key for operation.

35 6. In a machine of the class described, the combination of a group of depressible keys, said keys adapted to be manually selected and manually depressed; a member carried by each key and adapted to be moved relatively thereto in a direction at right angles to the direction of movement of said keys while being depressed; selectively operable automatic means cooperating 45 with each of said members to selectively move any one of the members relatively to its associated key to automatically select said associated key for operation; and an automatically operable device adapted to engage the selectively actuated member to automatically depress its associated key.

50 7. In a machine of the class described, the combination of a bank of depressible keys adapted to be manually selected and manually depressed; automatically operated means to automatically depress any key; and a selectively operable coupling member associated with each key to 55 couple its respective key to said automatically operated means to cause the key associated with the selected member to be automatically depressed by said means.

55 8. In a machine of the class described, the combination of a bank of depressible keys adapted to be manually selected and manually depressed; automatically operated means to automatically depress any key; a selectively operable coupling member associated with each key to 60 couple its respective key to said automatically operated means to cause the key associated with the selected member to be automatically depressed by said means; and electromagnetic means to actuate said coupling member.

70 9. In a machine of the class described, the

combination of a bank of depressible keys adapted to be manually selected and manually operated; automatically operated means to automatically depress any key; a selectively operable coupling member associated with each key to couple its respective key to said automatically operated means to cause the key associated with the selected member to be automatically depressed by said means; and electromagnet associated with each key; and means connected to each coupling member and operable by its associated electromagnet to move the coupling member into cooperation with said automatically operated means.

10. In a machine of the class described, the combination of a bank of depressible keys adapted to be manually selected and manually depressed; automatically operated means to automatically depress any key; a selectively operable coupling member associated with each key to couple its respective key to said automatically operated means to cause the key associated with the selected member to be automatically depressed by said means; means to retain any depressed key in its depressed position; an electromagnet associated with each key; and means connected to each coupling member and operable by its associated electromagnet to move the coupling member into cooperation with said automatically operated means while said key is in its normal undepressed position, and to move said coupling member out of coupling position with said automatically operated means after said key is locked in its depressed position.

11. In a machine of the class described, the combination of a bank of depressible keys adapted to be manually selected and manually depressed, and also adapted to be automatically selected and automatically depressed; means automatically operated to depress any key selected; means to retain any depressed key in its depressed position; means carried by each key and adapted to be shifted into cooperative relation with said automatically operated depressing means; and a device including a rockable member associated with each of the means carried by said keys and said device adapted to be selectively automatically actuated to cause the rockable member to shift the means carried by the keys into cooperative relation with the automatically operated depressing means to cause the latter upon operation thereof, to depress the selected key, and to cause said rockable member to restore the means carried by the key to normal position after said key is retained in depressed position.

12. In a machine of the class described, the combination of a bank of depressible keys adapted to be manually selected and manually depressed, and also adapted to be automatically selected and automatically depressed; means automatically operated to depress any key selected; means to retain any depressed key in its depressed position; means carried by each key and adapted to be shifted into cooperative relation with said automatically operated depressing means; and a device associated with each of the means carried by said keys and adapted to be selectively automatically actuated to shift the means carried by the keys into cooperative relation with the automatically operated depressing means to cause the latter upon operation thereof, to depress the selected key, each of said devices being automatically actuated to shift the means carried by its associated key back to normal

position after the selected key is locked in its depressed position.

13. In a machine of the class described, the combination of a bank of depressible keys adapted to be manually selected and manually depressed, and also adapted to be automatically selected and automatically depressed; a member common to all keys; means to automatically operate said member to depress any selected key; an element rigidly supported by each key, a coupling device slidably mounted in each element and normally in ineffective position; and automatically operable means cooperating with each coupling device and selectively actuated to move the associated coupling device into effective position to couple its associated key with said common member.

14. In a machine of the class described, the combination of a bank of depressible keys adapted to be manually selected and manually depressed, and also adapted to be automatically selected and automatically depressed; a member common to all keys; means to automatically operate said member to depress any selected key; means to lock any depressed key in its depressed position; an element rigidly supported by each key; a coupling device slidably mounted in each element and normally in ineffective position; and automatically operable means cooperating with each coupling device and selectively actuated to shift the associated coupling device into effective position, said automatically operable cooperating means also being actuated to slide the selected coupling device from effective to ineffective position after the depressed key has been locked in its depressed position.

15. In a machine of the class described, the combination of a bank of depressible keys adapted to be manually selected and manually depressed, and also adapted to be automatically selected and automatically depressed; a member common to all keys; means to automatically operate said member to depress any selected key; an element rigidly supported by each key; a slideable device mounted in each element and adapted to be moved into cooperative relation with said member, but normally retained in ineffective position; and an electromagnetic device connected to each slideable device and adapted to be selectively operable to move its connected slideable device into effective position into cooperative relation with said common member to cause the associated key to be depressed upon operation of said common member.

16. In a machine of the class described, the combination of a bank of depressible keys adapted to be manually selected and manually depressed, and also adapted to be automatically selected and automatically depressed; a member common to all keys; means to automatically operate said member to depress any selected key; means to retain any depressed key in its depressed position; an element rigidly supported by each key; a slideable device mounted in each element and adapted to be moved into cooperative relation with said member, but normally retained in ineffective positions; an electromagnetic device connected to each slideable device and adapted to be selectively operable to move its connected slideable device into effective position into cooperative relation with said common member to cause the associated key to be depressed upon operation of said common member; and means to selectively energize the electromagnets to cause their selective operation and to deenergize the selected elec-

tromagnet after the selected depressed key is retained in its depressed position, to cause said selected electromagnet to move its connected slideable device back to ineffective position.

17. In a machine of the class described, the combination of a plurality of manually operable data-determining devices; selectively operable means associated with said devices to automatically select any one of said devices for operation; means to automatically operate the selected one of said devices; means to retain the operated device in operated position; and means to select and actuate any one of said selectively operable means to cause said selectively operable means to select an appropriate one of said devices and to restore said selectively operable means to normal position after said selected device is retained in its operated position.

18. In a machine of the class described, the combination of a plurality of manually operable data determining devices, each device having one end thereof constructed so as to be manually selectable and manually operable to move the opposite end of the selected and operated device into a specific data-determining and controlling position; a slidably mounted member associated with each of said devices and normally in an ineffective position; common means automatically operable to cooperate with any one of said members when any one of the members is in effective position, to operate the associated device to move said opposite end of said device into a specific data-determining and controlling position; and means to selectively and automatically move any one of said members into an effective position into cooperative relation with said common means.

19. In a machine of the class described, the combination of a manually operable data-determining member having one end in position to effect an operation of said member when said one end is manually moved; a movable device associated with said member intermediate said one end and the other end of the member and normally in an inactive position, but adapted to be automatically moved into an active position; means to move its device into active position; and means to engage said device to operate said member automatically.

20. In a machine of the class described, the combination of a data-determining member; a movable device associated with said member intermediate the ends of the member and normally in an inactive position, but adapted to be moved automatically into active position; means automatically operable to engage said device when the device is in its active position to operate said member automatically; means to retain said member in its operated position; and an element to move said device into its active position prior to the operation of said automatically operable means and to restore said device to its inactive position after operation of said automatically operable means.

21. In a machine of the class described, the combination of a normally manually depressible key having a head to facilitate manual depression of the key; a member carried by the key below the head thereof and adapted to be moved relatively to the key in a direction at right angles to the direction of depression movement of the key, said member being normally in an inactive position and movable with said key upon manual depression thereof; automatically operable means to move said member relatively to the key to

condition the key for automatic depression; a device operable to engage and move said member in the direction of the depression movement of the key to automatically depress said key; and means to actuate said device after said member has been moved into active position.

22. In a machine of the class described, the combination of a normally manually depressible key having a head to facilitate manual depression of the key; a member carried by the key below the head thereof and adapted to be moved relatively to the key in a direction at right angles to the direction of depression movement of the key, said member being normally in an inactive position and movable with said key upon manual depression thereof; retaining means having a slideable connection with said member to retain the member in its normal inactive position prior to, during, and after manual depression of said key, automatically operable means to actuate said retaining means to cause movement of said member into its active position prior to a manual depression of the key to condition said key for automatic depression; a device operable after said member has been moved into its active position to engage and move the member in the direction of the depression movement of the key to effect an automatic depression of said key; means to lock said key in its automatically depressed position; and means to actuate said retaining means to move said member to its inactive position after automatic depression of the key.

23. In a machine of the class described, the combination of a normally manually depressible key having a head to facilitate manual depression; automatically operable means cooperating with said key below the head thereof to condition said key for automatic depression; means to retain said automatically operable means in inactive position prior to, during, and after manual depression of said key; means to actuate said automatically operable means prior to a manual depression of said key; and means automatically operable to depress said key after the key has been conditioned for automatic depression.

24. In a machine of the class described, the combination of a normally manually depressible key having a head to facilitate manual depression of the key; automatically operable means associated with said key below the head thereof to automatically depress said key; means to retain said automatically operable means in inactive position prior to, during, and after manual depression of said key; and means to actuate said automatically operable means prior to a manual depression of said key.

25. In a machine of the class described, adapted to be released for a normal cycle of operation in one instance and also adapted to be released for a preliminary cycle of operation followed by a normal cycle of operation, the combination of a common driving means for all cycles of operation; a driven shaft for the normal cycle of operation; a driven shaft for the preliminary cycle of operation; a normally ineffective clutch intermediate the driving means and the first driven shaft; a normally ineffective clutch intermediate the driving means and the second driven shaft; a clutch releasing means operable to release the first clutch; mechanism actuated by the clutch releasing means to release the second clutch and simultaneously prevent release of the first clutch, to cause the sec-

ond clutch to actuate the second driven shaft to effect a preliminary operation cycle of operation; and means to restore said mechanism during said preliminary cycle, to release said first clutch to cause said first clutch to actuate the first driven shaft to effect a normal cycle of operation immediately following the completion of the preliminary cycle.

26. In a machine of the class described, adapted to be released for a preliminary cycle of operation followed by a normal cycle of operation, the combination of a common driving means for all cycles of operation; a driven shaft for the normal cycle of operation; a driven shaft for the preliminary cycle of operation; a normally ineffective clutch intermediate the driving means and the first driven shaft; a normally ineffective clutch intermediate the driving means and the second driven shaft; a member to hold the first clutch ineffective; a member to hold the second clutch ineffective; means to retain the first member in position to hold the first clutch ineffective; means to retain the second member in position to hold the second clutch ineffective; means to actuate the first retaining means to release the first member; devices operated by the first retaining means to actuate the second retaining means to release the second member and to simultaneously engage the first member to prevent said first member from releasing the first clutch, the release of the second clutch member causing an operation of the second driven shaft to effect a preliminary cycle of operation; and means to restore said devices to normal position during said preliminary cycle, to disengage said devices from said first member to cause the first member to release the first clutch to cause an operation of the first driven shaft to effect a normal cycle of operation immediately following the completion of the preliminary cycle.

27. In a machine of the class described, adapted to be released for a normal cycle of operation in one instance and also adapted to be released for a preliminary cycle of operation followed by a normal cycle of operation, the combination of a common driving means for all cycles of operation; a driven shaft for the normal cycle of operation; a driven shaft for the preliminary cycle of operation; a normally ineffective clutch intermediate the driving means and the first driven shaft; a normally ineffective clutch intermediate the driving means and the second driven shaft; a member to hold the first clutch ineffective; a member to hold the second clutch ineffective; means to retain the first member in position to hold the first clutch ineffective; means to retain the second member in position to hold the second clutch ineffective; means to actuate the first retaining means to release the first member; devices operated by the first retaining means to actuate the second retaining means to release the second member and to simultaneously engage the first member to prevent said first member from releasing the first clutch, the release of the second clutch member causing an operation of the second driven shaft to effect a preliminary cycle of operation; means to restore said devices to normal position during said preliminary cycle to disengage said devices from said first member to cause the first member to release the clutch to cause an operation of the first driven shaft to effect a normal cycle of operation immediately following the

completion of the preliminary cycle; a plurality of manually operable means, any one of which causes the actuating means for the first retaining means to operate; and means controlled by an operation of certain of said manually operable means for preventing operation of said devices thus causing a normal cycle of operation only.

28. In a machine of the class described, 10 adapted to be released for a normal cycle of operation in one instance and also adapted to be released for a preliminary cycle of operation followed by a normal cycle of operation, the combination of a common driving means for all 15 cycles of operation; a driven shaft for the normal cycle of operation; a driven shaft for the preliminary cycle of operation; a normally ineffective clutch intermediate the driving means and the first driven shaft; a normally ineffective 20 clutch intermediate the driving means and the second driven shaft; a member to hold the first clutch ineffective; a member to hold the second clutch ineffective; means to retain the first member in position to hold the first clutch ineffective; 25 means to retain the second member in position to hold the second clutch ineffective; means to actuate the first retaining means to release the first member; devices operated by the first retaining means to actuate the second retaining 30 means to release the second member and to simultaneously engage the first member to prevent said first member from releasing the first clutch, the release of the second clutch member causing an operation of the second driven shaft 35 to effect a preliminary cycle of operation; and means associated with said devices to prevent operation of the devices to prevent engagement of the first member by the devices to prevent operation of said preliminary cycle and cause a 40 normal cycle of operation only.

29. In a machine of the class described, 45 adapted to be released for a normal cycle of operation in one instance and also adapted to be released for a preliminary cycle of operation followed by a normal cycle of operation, the combination of a common driving means for all cycles of operation; a driven shaft for the normal cycle of operation; a driven shaft for the preliminary cycle of operation; a normally ineffective clutch 50 intermediate the driving means and the first driven shaft; a normally ineffective clutch intermediate the driving means and the second driven shaft; a member to hold the first clutch ineffective; a member to hold the second clutch ineffective; means to retain the first member in position to hold the first clutch ineffective; means to retain the second member in position to hold the second clutch ineffective; means to actuate the first retaining means to release the first member; devices operated by the first retaining 55 means to actuate the second retaining means to release the second member and to simultaneously engage the first member to prevent said first member from releasing the first clutch, the release of the second clutch member causing an operation of the second driven shaft to effect a preliminary cycle of operation; a plurality of 60 manually operable means any one of which causes the actuating means for the first retaining means to operate; and means associated with said devices and normally in a position to prevent operation of the devices to prevent engagement of the first member by the devices to prevent operation of said preliminary cycle and cause a normal cycle of operation only, said last mentioned

means being controlled upon operation of certain of said manipulative devices to effect a delay of said normal cycle of operation until after a preliminary cycle of operation.

30. In a machine of the class described, adapted to be released for a normal cycle of operation in one instance and also adapted to be released for a preliminary cycle of operation followed by a normal cycle of operation, the combination of a common operating means for all cycles of operation; a normally ineffective driving means for the preliminary cycle; a normally ineffective driving means for the normal cycle; means to retain the first driving means in ineffective position; means to retain the second driving means in ineffective position; a device operable to release the second retaining means; a device operable to release the first retaining means; and means intermediate said devices and operable by the first device to actuate the second device to release the first retaining means, and simultaneously prevent the second retaining means from releasing the second driving means.

31. In a machine of the class described, adapted to be released for a normal cycle of operation in one instance and also adapted to be released for a preliminary cycle of operation followed by a normal cycle of operation, the combination of a common operating means for all cycles of operation; a normally ineffective driving means for the preliminary cycle; a normally ineffective driving means for a normal cycle; means to retain the first driving means in ineffective position; means to retain the second driving means in ineffective position; a device operable to release the second retaining means; a device operable to release the first retaining means; means intermediate said devices and operable by the first device to actuate the second device to release the first retaining means, and to simultaneously prevent the second retaining means from releasing the second driving means; and means to control said intermediate means to prevent its operation, thus causing the release of the second driving means only to cause operation of the normal cycle only.

32. In a machine of the class described, adapted to be released for a normal cycle of operation in one instance and also adapted to be released for a preliminary cycle of operation followed by a normal cycle of operation, the combination of a common operating means for all cycles of operation; a normally ineffective driving means for the preliminary cycle; a normally ineffective driving means for the normal cycle; means to retain the first driving means in ineffective position; means to retain the second driving means in ineffective position; a device operable to release the second retaining means; a device operable to release the first retaining means; means intermediate said devices and operable by the first device to actuate the second device to release the first retaining means and simultaneously prevent the second retaining means from releasing the second driving means; and means to restore the second device to normal position to cause it to release the second retaining means to release the second driving means immediately following operation of the first driving means.

33. In a machine of the class described, adapted to be released for a normal cycle of operation in one instance and also adapted to be released for a preliminary cycle of operation, followed by an automatic normal cycle of operation, the combination of a common operating means

for all cycles of operation; a normally ineffective driving means for the preliminary cycle; a normally ineffective driving means for the normal cycle; means to retain the first driving means in ineffective position; means to retain the second driving means in ineffective position; a device operable to release the second retaining means; a device operable to release the first retaining means; means intermediate said devices and operable by the first device to actuate the second device to release the first retaining means to render the first driving means effective; and means carried by the second retaining means and engaged by the intermediate means upon its operation to hold the second retaining means in retaining position to prevent operation of the second driving means.

34. In a machine of the class described, adapted to be released for a normal cycle of operation in one instance and also adapted to be released for a preliminary cycle of operation, followed by an automatic normal cycle of operation, the combination of a common operating means for all cycles of operation; a normally ineffective driving means for the preliminary cycle; a normally ineffective driving means for the normal cycle; means to retain the first driving means in ineffective position; means to retain the second driving means in ineffective position; a device operable to release the second retaining means; a device operable to release the first retaining means; means intermediate said devices and operable by the first device to actuate the second device to release the first retaining means to render the first driving means effective; means carried by the second retaining means and engaged by the intermediate means upon its operation to hold the second retaining means in retaining position to prevent operation of the second driving means; and means to restore said intermediate means to normal position to cause it to be disengaged from the means carried by the second retaining means to release the second retaining means upon completion of operation of the first driving means.

35. In a machine of the class described, adapted to be released for a normal cycle of operation in one instance and also adapted to be released for a preliminary cycle of operation, followed by an automatic normal cycle of operation, the combination of a common operating means for all cycles of operation; a normally ineffective driving means for the preliminary cycle; a normally ineffective driving means for the normal cycle; means to retain the first driving means in ineffective position; means to retain the second driving means in ineffective position; a device operable to release the second retaining means; a device operable to release the first retaining means; means intermediate said devices and operable by the first device to actuate the second device to release the first retaining means to render the first driving means effective; means carried by the second retaining means and engaged by the intermediate device upon its operation to hold the second retaining means in retaining position to prevent operation of the second driving means; and means to control said intermediate means to prevent its operation, thus causing the release of the second driving means only.

36. In a machine of the class described, the combination of a plurality of data-determining devices adapted to be manually selected and manually operated, and also adapted to be automatically selected and automatically operated; means to drive the machine through a normal

cycle of operation; means to drive the machine through a preliminary cycle of operation; means to automatically select any one of said devices for operation; means to effect an operation of said first driving means; means to effect an operation of said second driving means to cause a preliminary cycle of operation and simultaneously prevent operation of the first driving means; means operable during said preliminary cycle to operate the selected device; means to lock the selected and operated device in operated position; means operable during said preliminary cycle of operation to effect an operation of said first driving means to cause an automatic normal cycle of operation immediately following the completion of said preliminary cycle of operation; and means operable during said automatic normal cycle to operate said locking means to release the automatically selected and automatically operated device.

37. In a machine of the class described, the combination of a plurality of data-determining devices adapted to be manually selected and manually operated and also adapted to be automatically selected and automatically operated; means to drive the machine through a normal cycle of operation; means to drive the machine through a preliminary cycle of operation; means to automatically select any one of said devices for operation; means to effect an operation of said first driving means; means to effect an operation of said second driving means to cause a preliminary cycle of operation and to simultaneously prevent operation of the first driving means; means operable during said preliminary cycle of operation to actuate said automatic selecting means to cause automatic selection of said devices; means operable during said preliminary cycle to operate the selected device; means to lock the selected and operated device in operated position; means operable during said preliminary cycle to effect an operation of said first driving means to cause an automatic normal cycle of operation immediately following the completion of said preliminary cycle of operation; means operable during said automatic normal cycle of operation to operate said locking means to release the automatically selected and automatically operated device; and a plurality of manipulative devices certain of which controls the means which effects operation of said first driving means and also controls the means which effects operation of said second driving means, to cause said preliminary cycle of operation and said automatic normal cycle of operation immediately thereafter, certain other of said manipulative devices when operated, following a manual selection and manual operation of any of the data-determining devices, causing an operation of said means which effects operation of said first driving means, to cause a normal cycle of operation only.

38. In a machine of the class described, having a bank of data controlling devices adapted to be manually selected and manually operated and also adapted to be automatically selected and automatically operated; means associated with said devices to cause said automatic selection thereof; means to cause automatic operation of the automatically selected device; and means operable prior to said automatic selection and said

automatic operation of any device to automatically release any of said devices which were manually depressed prior to said automatic selection and operation of any device.

39. In a machine of the class described, the combination of a bank of data controlling devices adapted to be manually selected and operated; means associated with said devices to automatically select and operate any of said devices; and means to automatically release any manually selected and operated device prior to said automatic selection and operation of any of said devices.

40. In a machine of the class described, the combination of a data-determining member adapted to be manually depressed in one instance and automatically depressed in another instance; means to retain said member in its depressed position when manually depressed and/or when automatically depressed; and means to automatically operate said retaining means to release said depressed member after a manual depression thereof and prior to an automatic depression thereof.

41. In a machine of the class described, the combination of a data determining member adapted to be manually depressed and also adapted to be automatically depressed; a device to retain said member in depressed position when manually depressed and/or when automatically depressed; means to move said retaining device to release said depressed member; and means to control said moving means automatically to effect an operation of said moving means following a manual depression of said member immediately prior to an automatic depression of said member.

42. In a machine of the class described, adapted to perform a normal cycle of operation and also adapted to perform a preliminary cycle of operation followed by an immediate automatic normal cycle of operation, the combination of a bank of data controlling members adapted to be manually operated to control the entry of data in the machine during said first normal cycle of operation, said members also adapted to be automatically operated during said preliminary cycle of operation to control the entry of data in the machine during said automatic normal cycle of operation which follows said preliminary cycle of operation; and means operable during said preliminary cycle to automatically release any manually depressed data controlling member which was in depressed position immediately prior to said automatic operation of said data controlling members.

43. In a machine of the class described, adapted to be operated through a normal cycle of operation to enter data into the machine, the combination of manually operable data determining members to control the entry of such data during said normal cycle of operation, said machine also adapted to perform a preliminary cycle of operation followed by an immediate automatic normal cycle of operation to enter data into the machine during said automatic normal cycle; means operable during said preliminary cycle to automatically release any data determining member which might have been manually depressed between said first normal cycle of operation and said preliminary cycle of operation; and means operable during preliminary cycle of operation to automatically operate any of said data determining members to control the entry of data into the machine during said normal cycle of operation which auto-

matically follows said preliminary cycle of operation.

44. In a machine of the class described, the combination of a plurality of data determining devices adapted to be manually selected and manually operated and also adapted to be automatically selected and automatically operated; means to drive the machine through a preliminary cycle of operation; means to automatically select any one of said devices for operation; means to effect an operation of said first driving means; means to effect an operation of said second means to cause a preliminary cycle of operation and to simultaneously prevent operation of the first driving means; means operable during said preliminary cycle of operation to automatically release any of said data determining devices that were operated prior to said preliminary cycle of operation; means operable during said preliminary cycle of operation to actuate said automatic selecting means to cause automatic selection of said data determining devices; means operable during said preliminary cycle to operate the selected data determining devices; means operable during said preliminary cycle to effect on operation of said first driving means to cause an automatic normal cycle of operation immediately following the completion of said preliminary cycle of operation; and a plurality of manipulative devices certain of which controls the means which effects operation of said first driving means and also con-

trols the means which effects operation of said second operation of said second driving means to cause said preliminary cycle of operation and said automatic normal cycle of operation immediately thereafter, certain other of said manipulative devices when operated, following a manual selection and manual operation of any of said data determining devices causing an operation of said means which effects operation of said first driving means to cause a normal cycle of operation only.

EDWARD J. CAREY.
